UNITED STATES PATENT OFFICE

102,986

DESIGN FOR A TEXTILE FABRIC

Eugene Irving Hanson, New York, N. Y.

Application October 23, 1936, Serial No. 65,437

Term of patent 3½ years

To all whom it may concern:

Be it known that I, Eugene Irving Hanson, a citizen of the United States, residing in New York, city, county, and State of New York, have invented a new, original, and ornamental Design for a Textile Fabric, for which the following is a specification, reference being had to the accompanying drawing, forming part thereof, wherein—

Fig. 2 is an enlarged view of my new design, the same being hand drawn.

I claim:

The ornamental design for a textile fabric substantially as shown.

EUGENE IRVING HANSON.
